UNITED STATES PATENT OFFICE

JOHN GRAHAM, OF NEW YORK, N. Y.

DESIGN FOR GIMP.

Specification forming part of Design No. **11,154**, dated April 15, 1879; application filed February 19, 1879.
[Term of patent 7 years.]

To all whom it may concern:

Be it known that I, JOHN GRAHAM, of the city, county, and State of New York, have originated and designed a new Pattern for Gimp and other fabrics, of which the following is a specification.

The pattern, although especially intended for gimp, is not confined to it exclusively.

It consists of a body embellished with a zigzag stripe extending through the gimp first transversely, then at a right angle longitudinally for a short distance, preferably a little inward of the edge, then at right angles transversely, then longitudinally for a short distance near the other edge, and so on, and an intersecting straight stripe running through the gimp, and made preferably in contrasting colors.

The accompanying drawing illustrates a piece of gimp embellished with my pattern.

A designates the body of the gimp, which may have what is known as a "feathered edge," consisting of elongated loops *a*, or may have a plain straight edge, *b*. B designates a zigzag stripe extending through the gimp first transversely, then at a right angle longitudinally for a short distance near one edge, next at a right angle transversely again, then at a right angle longitudinally for a short distance near the other edge, and so on. C designates a straight stripe extending longitudinally through the middle portion of the gimp, and intersecting the zigzag stripe B passing outside one transverse portion, inside the next

one, and so on. These stripes B and C are preferably of a color different from that of the body of the gimp, and differ in color one from the other—for instance, the body of the gimp may be black, the zigzag stripe B may be yellow, and the straight intersecting stripe C may be red.

What I claim as my invention is—

1. A design or pattern for gimp, consisting of a body embellished with a zigzag stripe extending through it first transversely, then at a right angle longitudinally for a short distance, then at a right angle transversely, then at a right angle longitudinally for a short distance, then transversely, and so on, and a straight stripe intersecting the aforesaid rectangular stripe, substantially as specified.

2. A design or pattern for gimp, consisting of a body embellished with a zigzag stripe extending through it first transversely nearly to one edge, then at a right angle longitudinally for a short distance parallel with and a little inward of the edge, then at a right angle transversely, then at a right angle longitudinally for a short distance parallel with and a little inward of the other edge, then at a right angle transversely, and so on, and a straight stripe intersecting the aforesaid rectangular stripe, substantially as specified.

JOHN GRAHAM.
